UNITED STATES PATENT OFFICE.

MARIUS C. A. LATOUR, OF PARIS, FRANCE.

ELECTROMAGNETIC APPARATUS.

1,367,915.

Specification of Letters Patent. Patented Feb. 8, 1921.

Application filed August 2, 1917. Serial No. 184,181.

To all whom it may concern:

Be it known that I, MARIUS C. A. LATOUR, a citizen of the French Republic, residing at 10 Rue Auber, Paris, in the Republic of France, have invented certain new and useful Improvements in Electromagnetic Apparatus, of which the following is a specification.

This invention relates to electro-magnetic apparatus, by means of which a given mass can be made to oscillate or vibrate at any convenient frequency. In particular, the apparatus makes it possible to construct a vibrator that can be used for submarine 15 telegraphy or telephony.

The ordinary telephone represents the typical apparatus of the kind we are about to describe.

In the accompanying drawings, Figure 20 1 is a diagrammatic illustration of one form of my invention; Fig. 2 shows a modification in which a single pair of energizing coils is employed for both direct and alternating currents; Fig. 3 is a modification in 25 which a condenser is employed to prevent the return of the continuous current toward the source of alternating current; Fig. 4, illustrates a form of my invention in which opposed electro-motive forces are employed; Fig. 4^b shows a modification in which the 30 windings are arranged in the manner of a Wheatstone bridge; Fig. 5 illustrates an arrangement in which a unitary flow is produced by means of a mercury rectifier; Fig. 35 6 shows the magnets each provided with a series of poles for the purpose of reducing the magnetic flux per pair of poles; Fig. 7 shows a multipolar arrangement similar to that of Fig. 6 but with the vibratory mass 40 connected to opposed resilient means; and Fig. 8 shows the manner of obviating excessively high voltages across the winding by dividing the winding and inserting capacities.

45 Referring to Fig. 1, the mass of iron M is equally attracted by the two electromagnets A and A₁, excited by the source of continuous current S which supplies current to the windings E and E'. The windings B 50 and B₁ are traversed by an alternating current in such a way that the magnetic flux produced by the alternating current is added to that of the direct current in one magnet and is opposed in the other magnet, whereby 55 the attractive force of one magnet is neutralized and the other increased at each alterna-

tion. Under these circumstances it is clear that the mass of iron M will be subjected to an alternating attraction as soon as an alternating voltage is applied between the 60 terminals 1 and 2, and that consequently the mass will vibrate with the frequency of the alternating voltage that is applied at these terminals.

The direction of excitation of the two electromagnets may be such that the poles that face one another are of the same sign or of opposite signs; the only advantage of their being of opposite signs is in order that the continuous flux may not complete its 70 path in the material of the movable mass M.

According to the invention, the same windings may be used for the continuous-current excitation and for the alternating-current supply. Figs. 2, 3, 4 and 5 illustrate different constructional forms.

In Fig. 2 is shown a coil t, (which may be the secondary of the transformer connected to the source of supply of alternating current). The alternating current is led 80 into the apparatus between the terminals 1 and 2, while the source of continuous current S is branched between the point common to the windings B, B₁ and the middle point of the coil t. According to Fig. 3, 85 the windings B and B₁ of the electromagnets A and A₁ are both supplied with current by shunting across the terminals 1 and 2 of the source of alternating current; and the source of continuous current S is 90 branched at any point of the circuit of the windings B and B₁, considered as being connected in series relatively to this source. A condenser G prevents the return of the 95 continuous current toward the source of alternating current.

In Fig. 4, the source S has been divided into two parts S₁ and S₂, symmetrically arranged with respect to one another in such a way as to obviate the return of the 100 continuous current toward the source of alternating current in consequence of the electromotive forces S₁ and S₂, being put into opposition relatively to the source of alternating current.

105 The windings B and E may each be divided into two windings B, B' and B₁, B₁ so as to constitute the four arms of a Wheatstone bridge, as shown in Fig. 4^b. The alternating current will be led to the two ends 110 of one diagonal and the continuous current to the two ends of the other diagonal. The

two windings B , B' , as well as the two windings B_s , B_s' , constitute respectively the two opposite arms of the bridge.

- Finally it will be realized that the electromagnet may be fed with intermittent current obtained for instance by means of a rectifier. In Fig. 5 is illustrated the case in which the electromagnets are supplied with current by means of a mercury rectifier R , the cathode of which is excited by the source of continuous current S , the positive half-waves of the alternating current flowing into one electromagnet and the negative half-waves into the other.
- 15 The two electromagnets A , A_1 of Fig. 1 may be supplied with two-phase currents $I \sin t$ and $I \cos t$, led respectively to the coils B and B_1 , and all continuous-current excitation may be dispensed with.
- 20 Under these circumstances the attractions on the two faces of the armature M will be at the same instant proportional to $\sin^2 t$ and $\cos^2 t$.

The armature M will be urged by the difference between these two attractions, that is to say, by a force proportional to $\sin^2 t - \cos^2 t$.

The mass M therefore will vibrate at double the frequency of the two-phase currents that feed the apparatus, and perfectly symmetrical working will be obtained for the half-vibrations going and returning.

The use of two-phase current will lead to that of a two-phase generator, which might prove more economical both in construction and in efficiency than a monophase generator.

In the apparatus described the electromagnets and the movable mass M are laminated so as to eliminate the Foucault currents. The plates of the movable mass may be assembled by mere gripping. It is advantageous to reduce the volume of the mass M as much as possible. To this end multipolar apparatus will be constructed in practice, as illustrated in Fig. 6, so as to reduce the thickness of the magnetic circuits. The flux per pair of poles being reduced as much as is desired by multiplying the number of pairs of poles, it follows therefrom that as small a section as is desired may be adopted for the mass M . In fact it could even be constructed in the form of a thin full plate like the plate of a telephone.

55 In Fig. 7 it is assumed that the polar system is divided into two parts in such a way as to allow for the use of the spindle that controls the vibrating mass P , and in this figure springs R , R_1 have been shown which keep the mass M at rest in its mean position. For the springs R , R_1 any equivalent resilient device such as pneumatic pistons, membranes fastened along their peripheries or other suitable device may be substituted.

The air gap of the apparatus is in all cases made very small. The plate P , may be connected to the mass M through the medium of levers that increase the amplitude of the oscillations.

It is to be observed that in order to bring the value of the power factor of the apparatus to unity, it will be necessary to connect a capacity in series with the alternating-current circuit, unless the elasticity of the system suffices for the purpose.

On account of this elasticity it may even be realized that the apparatus supplies wattless current to the network and it may be utilized for this special purpose.

80 Suitable air-holes may be provided for ventilation.

In order to obviate excessively high voltage on the winding traversed by the alternating current it may be divided into several sections, each of which would comprise a capacity C in series, as illustrated in Fig. 8.

The alternator employed for the purpose of supplying current to the apparatus might in the case of submarine apparatus be the same one that serves for the radiotelegraphic station if required.

The apparatus that we have described is applicable to all cases in which it is desired to make a mass oscillate whatever may be the practical result obtained with such oscillation. It may in particular be converted into a simple telephone.

The apparatus works reversibly, that is to say, if the mass M is set in oscillation an electromotive force appears in the coils B , B_1 . In this way an electrical generator is obtained which can operate as an acoustical receiver. It may be indicated that the apparatus is utilizable for submarine telegraphy as above set forth in the prelude to the descriptive portion of the specification. Moreover, referring particularly to Fig. 7 of the drawing, it is observed, by way of further illustration of the use of my invention, that the piston p upon being plunged into water, oscillates and provides for indicating submarine telegraphy, as for example by the well known Fessenden oscillator. Like said oscillator, my apparatus may be employed either as a generator, or as a receiver for submarine telegraphy.

What I claim and desire to secure by Letters Patent of the United States is:—

1. Electro-magnetic apparatus including opposed sets of electro-magnetic poles, a magnetizable body vibratably positioned between said poles, a continuous-current energizing means for certain sets of poles and an alternating current-energizing means for alternating sets of poles.

2. Electro-magnetic apparatus, including opposed sets of electro-magnetic poles, a magnetizable body vibratably positioned between said poles, the poles of each electro-

magnet having alternating polarity, a continuous-current energizing means for certain poles and an alternating current-energizing means for alternating sets of poles.

5 3. Electro-magnetic apparatus, including oppositely arranged electro-magnets, a magnetizable body vibratably positioned between said electro-magnets, each of said electro-magnets having several poles integral there-
10 with, the poles of each electro-magnet having alternating polarity, the poles of one magnet being opposite those of the other magnet and arranged in sets, a continuous current-energizing means for certain sets of
15 poles and an alternating current-energizing means for alternating sets of poles.

4. Electro-magnetic apparatus, including opposed electro-magnets, a body of magnetic material vibratably positioned between said
20 electro-magnets, a source of continuous current and a source of alternating current having capacities connected in series there-

with, said sources being connected to the energizing coils of said electro-magnets.

5. Electro-magnetic apparatus, comprising oppositely arranged electro-magnets, each having a plurality of pairs of poles, the poles of one being alined with the poles of the other, a body of magnetic material interposed therebetween, windings on alined 30 poles of the electromagnets, said windings being connected in series with a source of continuous electric current, windings on other of the alined poles of the electro-magnets, said latter windings being connected 35 in series with a source of alternating current for the purpose set forth.

In testimony whereof I affix my signature in presence of two witnesses.

MARIUS C. A. LATOUR.
